UNITED STATES PATENT OFFICE.

CHARLES W. ROBINSON, OF HAMILTON, ONTARIO, CANADA, ASSIGNOR, BY MESNE ASSIGNMENTS, TO INTERNATIONAL HARVESTER CORPORATION, A CORPORATION OF NEW JERSEY.

GRAIN-BINDER.

1,211,627.

Specification of Letters Patent.

Patented Jan. 9, 1917.

Application filed August 29, 1913. Serial No. 787,285.

To all whom it may concern:

Be it known that I, CHARLES W. ROBINSON, a citizen of the United States, residing at Hamilton, in the county of Wentworth and Province of Ontario, Dominion of Canada, have invented certain new and useful Improvements in Grain-Binders, of which the following is a full, clear, and exact specification.

10 My invention relates to grain binders, and comprises improvements in tripping mechanism forming a part of the associated mechanism of this class of machine; the object of my invention being to provide a mechanism efficient in operation, readily adjusted to meet the various requirements in the operation of the machine, and capable of yielding under excessive or abnormal conditions. These objects are obtained by means of 15 mechanism, one embodiment of which is illustrated in the accompanying drawings, in which—

Figure 1 is an end elevation of a grain binder having my invention forming a part 20 thereof; Fig. 2 is a top plan view of Fig. 1; Fig. 3 is a side elevation of a trip stop forming an essential element of my invention; and Fig. 4 is a top plan view of Fig. 3.

The same reference characters designate 25 like parts throughout the several views.

1 represents a part of the main frame of a grain binder sufficient to illustrate the operation of my invention, and having a packer shaft 2, a needle shaft 3, a knotter driving shaft 4, a knotter shaft 5, and a tripping and compressor shaft 6 journaled thereon.

7 represents the cam wheel secured to the knotter shaft 5, 8 the compressor lever pivoted upon the binder frame and having the 30 roller 9 upon one end adapted to engage with the cam rim 10 forming part of the wheel 7, and its opposite end connected with the tripping and compressor shaft 6 by means of a link 11 and a yoke member 12, 35 a compression spring 13 surrounding the link and yieldingly resisting a rocking movement of the shaft 6 in one direction, all of the foregoing parts being common in this type of machine.

40 45 50 14 represents a trip stop loosely mounted upon the needle shaft 3 and having a tail member 15 integral with the stop and adapted to engage with a toe member 16 in-

tegral with the lower end of the yoke member 12, a barrel member 17 adapted to 55 slidably receive a spring-pressed plunger having a head portion 18 and a reduced shank portion 19 that is threaded at its free end and slidably received by an opening in the cross wall 20 of the barrel member, and 60 21 represents an adjusting nut whereby the operative length of the stop may be controlled, the plunger being yieldingly held toward an operative position by means of a coiled spring 22 encircling the reduced end 65 of the plunger and operative between the cross wall 20 and a shoulder portion 23 in a manner to press the plunger outward, and 24 represents a pin carried by the plunger and received by a longitudinally disposed 70 slot 25 in the side wall of the barrel member 17, the pin being operative to limit a sliding movement of the plunger in the direction of the operative force of the spring 22.

26 represents a laterally extending ear 75 member disposed at one side of the barrel member and having an opening that slidably receives the body portion of a link member 27, one end of the link being pivotally connected with the needle crank 80 28, the movement of which is controlled in a well-known way by means of the pitman 29 connecting it with the cam wheel 7.

30 represents a coiled spring carried by 85 the link 27 and operative between the ear member 26 and an adjusting nut 31 threaded upon the free end of the link, the spring being operative to yieldingly control an angular movement of the stop relative to the needle crank.

90 95 32 represents a common form of clutch controlling pawl that coacts with a driving member 33 secured to the packer shaft 2 and controlled by the trip stop in a well-known way.

In the operation of my invention, when the free end of the trip stop is released from the clutch pawl by the action of the trip shaft, the power transmission gearing carried by the packer shaft and connected with 100 the cam wheel 7 causes the wheel to be turned through one revolution and the needle shaft to be rocked through a predetermined degree of angular movement, carrying the trip stop with it, and as the 105 needle shaft returns to its initial position,

an ear member 34 integral with the binder frame engages with the ear member 35 forming part of the trip stop, in a manner to limit the action of the spring 30.

5 The utility of my invention is the readily adjustable means for controlling the operative length of the trip stop and the means permitting the stop to yield automatically against the shock of the binder "coming 10 home," and insures that the roller 9 will properly engage with the stop portion 36 of the cam rim 10, as shown in Fig. 1.

While I have in this application described one form which my invention may assume 15 in practice, it is to be understood, of course, that the embodiment shown herein for purposes of illustration is susceptible of modification without departing from the spirit of the invention.

20 What I claim as my invention, and desire to secure by Letters Patent, is:

1. A trip stop for binders comprising a body portion and a head portion reciprocable with respect to the body portion and adapted 25 to engage a movable part of the binder mechanism.

2. A trip stop for binders comprising a body portion and a yieldingly mounted head portion reciprocable with respect to the body 30 portion.

3. A trip stop for binders comprising a body portion and a yieldingly mounted head portion reciprocable with respect to the body portion, and means for adjusting the amount 35 of yielding thereof.

4. A trip stop for binders comprising a body portion and a yieldingly mounted head portion reciprocable with respect to the body portion, and means including a slot and pin 40 connection intermediate said head and body portion for limiting the movement of the former.

5. In combination, a rotating clutch member, and an oscillating spring controlled 45 trip stop comprising a body portion and a head portion reciprocable with respect to the body portion and disposed in the path of said clutch member.

6. In combination, a rotating clutch member, and an oscillating spring controlled trip 50 stop comprising a body portion and a head portion, said head portion being yieldingly mounted on said body portion and engageable with said clutch member and movable 55 in a path substantially tangential to the path thereof.

7. In a grain binder, in combination, a 60 tripping mechanism including a trip stop, and a clutch mechanism including a clutch controlling pawl, said trip stop comprising a body portion and a resiliently mounted head portion reciprocable with respect to the body portion, said head portion coöperating with said pawl in controlling said clutch mechanism.

8. A grain binder having, in combination, a tripping mechanism including a trip stop, and a clutch mechanism including a clutch controlling pawl, said trip stop comprising a body portion and a head portion reciprocable with respect to said body portion, said head portion being adjustable relative to said body portion and coöperating with said clutch pawl in controlling said clutch mechanism. 75

9. A grain binder having, in combination, a tripping mechanism including a trip stop and a clutch mechanism including a clutch controlling pawl, said trip stop being provided with a spring controlled longitudinally 80 slideable head coöperating with said pawl in controlling said clutch mechanism.

10. A grain binder having, in combination, a tripping mechanism including a trip stop and a clutch mechanism including a clutch controlling pawl, said trip stop being provided with an adjustable spring controlled longitudinally 85 slideable head engageable with said pawl in controlling said clutch mechanism. 90

11. A grain binder having, in combination, a tripping mechanism including a trip stop and a clutch mechanism including a clutch controlling pawl, said trip stop having a barrel formed portion and a clutch controlling head member slidably received by said barrel portion and engageable with said clutch pawl in controlling said clutch mechanism. 95

12. A grain binder having, in combination, a tripping mechanism including a trip stop and a clutch mechanism including a clutch controlling pawl, said trip stop being provided with an adjustable sliding head engageable with said clutch pawl in controlling said clutch mechanism, and means for limiting a sliding movement of said head in one direction. 100

13. A grain binder having, in combination, a tripping mechanism including a trip stop and a clutch mechanism including a clutch controlling pawl, said trip stop having a barrel portion, a clutch pawl engaging member slidably received by said barrel portion, and a pin carried by said pawl 115 engaging member engageable with said barrel portion to limit a sliding movement of said pawl engaging member in one direction.

14. A grain binder having, in combination, a tripping mechanism including a trip stop and a clutch mechanism, said trip stop being automatically extensible and retractile and coöperating with the clutch mechanism. 120

15. A grain binder having, in combination, a tripping mechanism including a trip stop and a clutch mechanism including a clutch controlling pawl, said trip stop having a barrel portion, a clutch pawl engaging member slidably received by said barrel 125 portion, and a pin carried by said pawl engaging member engageable with said barrel portion to limit a sliding movement of said pawl engaging member in one direction. 130

portion, a pin carried by said pawl engaging member engageable with said barrel portion in a manner to limit a sliding movement of said pawl engaging member in one 5 direction, a spring carried by said barrel portion operative to move said pawl engaging member in the same direction, and supplemental means for controlling the limit

of movement of said pawl engaging member in the same direction.

In testimony whereof I affix my signature 10 in the presence of two witnesses.

CHARLES W. ROBINSON.
